[57] ABSTRACT

An assembly comprising a mandrel having thereon spaced pattern discs and intervening split mandrel spacers each comprising two complementary parts in contact with the mandrel, these discs and spacers being clamped together facially. The assembly is used in a pattern disc preparation machine for breaking teeth of pattern discs of knitting machine pattern units.

The complementary mandrel spacer parts are either separate and unconnected or connected but readily separable for disengagement from the mandrel. The sides of such parts may be recessed to receive pattern unit spacers of smaller diameter.

The invention includes an upright assembling unit to facilitate assembly of disc and spacers on to a mandrel. It also includes a transfer unit for enabling the pattern discs and pattern unit spacers, on a mandrel from which the parts of the split mandrel spacers have previously been released and allowed to fall away, to be slid off the mandrel on to an aligned pattern unit spindle.

FIG. 10.

MANDREL ASSEMBLY FOR PATTERN DISC PREPARATION MACHINES

This invention relates to pattern disc preparation machines for breaking teeth off pattern discs for use on circular knitting machines, and is concerned more particularly with a mandrel assembly in such a machine for holding the discs and for loading and unloading the same from these assemblies.

In known disc preparation machines such a mandrel assembly usually consists of a series of circular spacers between adjacent discs and a locking means for holding the spacers and discs in a fixed longitudinal relationship. These spacers are wider than those used when the prepared discs are assembled in a pattern unit for use on the knitting machine. This is because the disc preparation machine requires sufficient space between each disc to permit of a relative longitudinal breaking movement between the discs and the teeth breakers and also because it is desirable to keep the height of a stack of discs in a pattern unit on a circular knitting machine to a minimum.

Accordingly, when taking prepared discs from a mandrel and putting them into a pattern unit for a knitting machine, it is necessary to take-off mandrel spacers and put on pattern unit spacers. This is a time consuming manual operation which can result in incorrect arrangement of the prepared discs in the pattern unit.

The object of the present invention is to provide, for use in a pattern disc preparation machine, an improved mandrel assembly designed to eliminate the aforesaid time consuming operation and hence any possibility of operator error in transferring prepared discs from a mandrel to a pattern unit.

According to this invention the improved mandrel assembly comprises a mandrel on which are loaded a series of pattern discs and spacers, said assembly being characterised in that it is furnished, between each disc and the immediately adjacent disc, with a mandrel spacer which is in at least two separate or connected complementary parts each in contact with the circumference of the mandrel.

In accordance with a further feature of the invention, the opposite side faces of the parts of each mandrel spacer may be arcuately recessed to receive smaller diameter complete circular pattern unit spacers.

It will be appreciated that the last mentioned feature enables the mandrel spacers to be removed and the prepared discs and pattern unit spacers to be passed directly onto a pattern unit.

The invention includes special tools which have been designed to facilitate the mandrel assembly and the transfer of discs to pattern units.

In order that the invention may be more clearly understood and readily carried into practical effect, a specific constructional example of said invention and variations thereof will now be described with reference to the accompanying drawings in which:

FIG. 1 is a cross-section through the mandrel assembly, showing a split mandrel spacer having two separate parts,

FIG. 2 is a detail axial section of a fragmentary portion of the said assembly taken on the line II — II of FIG. 1,

FIG. 3 is a view similar to FIG. 1 showing a split mandrel spacer having two connected parts,

FIG. 4 is a plan view of a mandrel in an assembling unit,

FIG. 5 is a front view of the mandrel and assembling unit as seen in the direction of arrow V in FIG. 4,

FIG. 6 is a plan view of a mandrel in an unloading unit,

FIG. 7 is a front view as seen in the direction of the arrow VII in FIG. 6,

FIG. 8 is a fragmentary front view of a mandrel and spacers in an alternative arrangement,

FIG. 9 is a view similar to FIG. 1 of a further alternative mandrel spacer arrangement, and

FIG. 10 is a detail plan view of the same as seen in the direction of the arrow in FIG. 9.

In FIGS. 1 and 2 are shown two separate split mandrel spacer parts 1 and 2. The opposite side faces of the complementary spacer parts are arcuately recessed at 1a and 2a to freely house smaller diameter pattern unit spacers 3, one per complete mandrel spacer. Thus, there is only one pattern unit spacer 3 adjacent to each pattern disc 4 when assembled on the pattern unit.

In order accurately to locate the pattern discs 4, the mandrel 5 has two longitudinally extending keys 6 and 7 fitted into it. To enable them to receive and clear these keys 6 and 7 the inner circumferential edges of the complementary mandrel spacer parts 1 and 2 have therein cut-outs 1b and 2b. It will therefore be appreciated that the mandrel spacers are so designed as to be completely interchangeable and reversible, thus making it possible to fit them incorrectly.

In FIG. 3 is shown an example of a mandrel spacer having two substantially semi-circular parts 8 and 9 which are pivotally connected together by a pin 10. The spacer parts 8 and 9 also have recesses 8a and 9a formed therein for accommodation of the pattern unit spacers 3, and cut-outs 8b and 9b to receive and clear the keys 6 and 7. In both of the spacer constructions illustrated in FIGS. 1 to 3, the spacers are held in position by means of an axially extending locking handle such as that depicted at 11 in FIG. 6. As will be seen in this figure the locking handle has an inner screw-threaded portion 11a for screwing into a tapped hole formed axially in an end of the mandrel and a shouldered outer portion 11b which is furnished with a knurled knob 11c and is adapted for contact with a hollow washer part w bearing on the corresponding end of the assemblage of discs 4 and mandrel spacers. By screwing in this handle the spacers 1, 2 (or 8, 9) are clamped and held, and by slackening it the sideways pressure holding the spacers is removed thereby enabling them to be easily removed.

To prevent the spacers shown in FIG. 3 from falling out accidentally, during assembly, it would be possible to fit to one part 8 a leaf spring 12 designed to latch into a notch 13 in the complementary part 9. But as this would make removal of the mandrel spacers an individual operation, each one having to be unlatched, it is preferred to adopt the construction of FIGS. 1 and 2 so that the separate and unconnected spacer parts 1 and 2 fall out when the sideways pressure thereon is relieved. This, however, presents problems of assembly which have been solved by the mechanism now to be described with reference to FIGS. 4 and 5.

FIGS. 4 and 5 show a completed mandrel assembly MA in position on a vertically disposed assembling unit AU. This unit comprises a base 14 having therein a hole 14a and a keyway 14b into which are respectively fitted

a projection 15 and a key 16 on the lower end of the mandrel assembly MA (viewed in an upright position). The assembly MA is also held steady by spaced supporting arms 17a of an upstanding support 17. Fixed into the top of this support 17 is a shaft 18 on which are pivotally mounted a pair of opposed comb holders 19 and 20 each of which is capable of being manually moved towards and away from the mandrel assembly MA. Attached to the comb holders 19 and 20, are combs 21 and 22 the prongs 21a and 22a of which, in their operative positions, project in between the pattern discs 4 and clamp the complementary spacer parts 1 and 2 firmly in position. The clamping action is effected by a purely manual operation during which the axially extending locking handle 11 (similar to that described with reference to FIG. 6) is tightened to secure all the spaced discs 4 and the intervening spacer parts 1 and 2 in position.

The assembling unit AU enables the mandrel 5 first to be placed vertically in position and the necessary discs 4 and spacers to be assembled thereon one after another in horizontal planes until a full complement of discs is assembled, whereafter the locking handle 11 is fitted and tightened to clamp the discs and spacers together axially and the combs 21 and 22 are brought radially into clamping arrangement with the complementary parts 1 and 2 of the split mandrel spacers.

The mandrel assembly MA is now ready to be placed on a disc preparation machine of any known form which it is not necessary to describe herein. One such machine is known as the "Stibematic Discmaster" which was first shown in Paris in June 1971 at the International Exhibition of Textile Machinery, although this machine did not, of course, have a mandrel with split spacers.

The discs having been prepared by breaking off selected peripheral teeth it is now necessary to remove these discs and the pattern unit spacers from the mandrel assembly and transfer them onto a pattern unit for fitting on to a knitting machine. For this purpose, a transfer unit such as that designated TU in FIGS. 6 and 7 is employed.

The transfer unit TU consists of a base 23 upon one end of which is pivotally mounted a mandrel assembly support 24. This support is U-shaped — comprising two spaced vertical arms 24a and 24c. The arm 24a has therein a hole 24b in which is located the projection 15 on the mandrel assembly MA. The other arm 24c supports the body of the said assembly. The key 16, which radially locates the mandrel assembly is held in position by a latch 25 having therein a cut-out 25a. This latch is pivotally attached, by means of a shoulder screw 26, to the arm 24a of support 24.

The support 24 is itself pivoted on a shoulder screw 27 the head and the shoulder of which are respectively located in a longitudinal recess 23a and a slot 23b formed in the base 23. The said support is further located by another shoulder screw 28 whose head and shoulder are respectively located in a recess 23c and a slot 23d also formed in the base 23. The slot 23d and recess 23c are partly arcuate and partly straight in the longitudinal direction of the base 23. This locating arrangement is accordingly such that the support 24 can be swung radially out of line on the transfer unit and can also be slid longitudinally with respect to such unit for purposes hereinafter to be described.

At the opposite end of the base 23 is a fixed bracket 29 onto which is attached a pattern unit support 30. The pattern unit, for the sake of simplicity in this description, will be regarded as simply comprising a spindle 31 fitted with keys 32 and 33 for radially locating the pattern discs 4. The spindle 31 is fastened onto a base 34 which locates in the support 30 with its driving shaft 35 in a hole 30a. The base 34 is held against rotation by means of a key 36 which is attached to the support 30 and engages in a keyway 34a in the said base.

A stud 37, fitted into a central hole 31a in the spindle 31, projects axially from the pattern unit PU and serves to locate the mandrel assembly MA by engagement in a hole 5a formed axially in the relevant end of the mandrel 5.

In operation, therefore, the mandrel assembly, with a set of prepared pattern discs thereon, is taken from the disc preparation machine and located in support 24 as previously described, but with the said support in the out-of-line position shown in FIG. 6. In this position the locking handle 11 is unscrewed and removed, thereby releasing the split spacer parts 1 and 2 which drop into a tray 38. The support 24 is then turned to a normal position in which the mandrel assembly MA is in co-axial alignment with the pattern unit PU. The support 24 is then slid longitudinally so that stud 37 is located in a hole 5a in the mandrel 5 as shown in FIG. 7. The mandrel 5 at this stage only has on it the pattern discs 4 and pattern unit spacers 3, these being slid off directly onto the pattern unit PU.

With this improved arrangement, a minimum amount of time is spent in removing the mandrel spacers and in fitting the pattern unit with its discs and spacers. Moreover, there is no possibility of any discs being incorrectly assembled. The pattern unit with its assembled discs and spacers is simply removed from the transfer unit TU, after its disc locking screw, which replaces the stud 37, has been fitted and placed on the knitting machine.

Pattern units on some types of knitting machines are so designed that the pattern unit spacers are the same diameter as the root diameter of the peripheral teeth on the pattern discs. In such a case it is not, of course, possible to accommodate a pattern unit spacer within a recess in a two-part mandrel assembly spacer.

The alternative arrangement illustrated in FIG. 8 is used on the mandrel assembly in a case where each pattern unit spacer 39 is of the same diameter as the mandrel spacer. In FIG. 8, each mandrel assembly spacer is represented by two complementary spacer parts 40 and 41. As will be seen in this figure, moreover, pattern unit spacer 39 and a mandrel spacer 40, 41 are placed side by side on the mandrel 5 between each pair of pattern discs 4.

The alternative mandrel spacer construction illustrated in FIGS. 9 and 10 consists of two complementary semi-circular spacer parts 42 and 43 which have respectively formed in their outer circumferential portions two opposed recesses 42a and 43a for accommodation of a leaf spring 44. The opposite ends of this spring are secured to the bottoms of the recesses 42a and 43a by means of rivets 45 and 46 respectively. The inner arcuate face of the semi-circular spacer part 42 is formed with a pair of circumferentially spaced and inwardly directed radial projections 42b and 42c. In a similar way, the spacer part 43 is formed with a pair of

radial projections 43b and 43c. As will be seen from FIG. 9, the only points of contact of the complementary spacer parts 42 and 43 with the mandrel 5 are constituted by the inner free ends of the said four radial projections. The latter are made thinner than the main bodies of the spacer parts in order to provide space for accommodation of pattern unit spacers 3 as previously described. The leaf spring 44 is shown in tension but when normally in an untensioned condition it holds the spacer parts 42 and 43 connected thereby open, i.e., splayed apart, so that they can freely pass respectively opposite sides of the mandrel 5.

I claim:

1. A mandrel assembly for fitting into a pattern disc preparation machine designed to break predetermined teeth off peripherally toothed pattern discs of knitting machine pattern units, said assembly being of a form comprising a mandrel, spaced peripherally toothed and centrally apertured pattern discs mounted on said mandrel, intervening mandrel spacers loaded onto the mandrel between said pattern discs, and locking means clamping the pattern discs and the spacers together axially and thereby holding them in a fixed relationship, said mandrel being formed with longitudinally extending key means which the said toothed pattern discs engage for securing the discs against rotation on the mandrel, each of said spacers being split into two complementary arcuate parts so that each part is movable radially onto and off of the mandrel, each in contact with the circumference of the mandrel but having in their inner circumferential edges cut-out means for receiving and clearing the key means.

2. A mandrel assembly according to claim 1, wherein the two complementary parts of each mandrel spacer are separate and unconnected so that when the axially exerted clamping pressure thereon is relieved these parts are free to fall out of the assembly.

3. A mandrel assembly according to claim 1, wherein the two complementary spacer parts are connected but readily separable for disengagement from the mandrel.

4. A mandrel assembly according to claim 1, wherein each split mandrel spacer comprises two substantially semi-circular parts which are pivotally connected together by a pin.

5. A mandrel assembly according to claim 1, wherein each split mandrel spacer comprises two substantially semi-circular parts which are connected by a leaf spring which, when in an untensioned condition, holds the said parts open, i.e., splayed apart.

6. A mandrel assembly according to claim 5, wherein the semi-circular parts of each mandrel spacer have respectively formed in their outer circumferential portions opposed recesses for accommodation of the leaf spring the opposite ends of which are secured to the bottoms of said recesses.

7. A mandrel assembly according to claim 1, wherein inner arcuate faces of the mandrel spacer parts are formed with inwardly directed radial projections arranged to contact the mandrel at circumferentially spaced points only, these projections being made thinner than the main bodies of the spacer parts to provide space for accommodation of whole pattern unit spacers of smaller diameter than the mandrel spacers.

8. A mandrel assembly according to claim 1, wherein the spaced pattern discs and the intervening mandrel spacers loaded on to the mandrel are clamped together

facially by an axially extending handle having an inner screwthreaded portion for screwing into a tapped hole formed axially in an end of the mandrel and a shouldered outer portion which is furnished with a knob and is adapted for contact with a washer part bearing on the corresponding end of the assemblage of pattern discs and spacers.

9. A mandrel assembly according to claim 1, which includes pattern unit spacers of the same diameter as the mandrel spacers, a pattern unit spacer and a mandrel spacer being disposed side by side on the mandrel between each pair of pattern discs.

10. A mandrel assembly according to claim 1, wherein the split mandrel spacers are thick in comparison with the relative thinness of the toothed pattern discs, and the side radial faces of the complementary parts of said spacers are facially recessed arcuately, providing complete circular recesses wherein are located relatively thin circular pattern unit spacers of smaller diameter than said mandrel spacers, there being one pattern unit spacer to each toothed pattern disc.

11. A mandrel assembly according to claim 10, wherein both of the opposite side faces of the split parts of each mandrel spacer are arcuately recessed to provide a circular pattern unit spacer-accommodating recess at each side of each mandrel spacer.

12. A method of handling pattern discs for knitting machine pattern units, comprising the steps of: assembling the discs onto a mandrel by first mounting and holding a circular mandrel with its axis extending vertically in an assembling unit, assembling onto the vertically mounted mandrel pattern discs and spacers, one after the other, the spacers being of the type which are split so as to comprise two complementary arcuate parts, each of which is movable in a radial direction onto and off of the mandrel, clamping the discs and spacers together facially in an axial direction and also clamping radially into contact with the mandrel the complementary parts of the split mandrel spacers.

13. The method of claim 12, further including the steps of: removing the pattern discs and the pattern unit spacers from the mandrel assembly and transferring the same to a pattern unit by placing the said assembly into a pivoted support of a transfer unit equipped also with a support by which is carried a keyed pattern unit spindle; turning the said mandrel assembly support out of line with the pattern unit spindle; thereupon relieving the axially exerted clamping pressure on the faces of the discs and spacers so that the complementary parts of the split mandrel spacers are released from the mandrel; next turning the mandrel assembly support into alignment with the pattern unit spindle; shifting said mandrel assembly support longitudinally to locate together and mandrel and the said spindle, and axially sliding the pattern discs and associated pattern unit spacers off the mandrel onto the pattern unit spindle.

14. For carrying out the method claimed in claim 12, a mandrel assembly combined with a vertically disposed assembling unit comprising a base with which the lower end of the mandrel is adapted to key; an upstanding support on the base having spaced arms for holding the mandrel steady; a vertical shaft fixed into said support; a pair of opposed comb holders which are pivotally mounted on this shaft and are movable towards and away from the mandrel having thereon an assemblage

of pattern discs and arcuately split complementary spacers; and combs which are attached to the comb holders and have prong means for projecting, in their operative positions, between the pattern discs and for clamping into contact with the mandrel complementary parts of the intervening split mandrel spacers.

15. For carrying out the method claimed in claim 13, a mandrel assembly having thereon an assemblage of pattern discs and arcuately split complementary spacers and a transfer unit means for facilitating removal of pattern discs and associated whole pattern unit spacers from said assembly and for transferring them onto a pattern unit for fitting onto a knitting machine, said transfer unit comprising a base; a mandrel assembly support pivotally mounted upon one end of said base and in which the mandrel assembly is located, cradled and latched in position; at the opposite end of the said base a fixed bracket; a pattern unit support attached to said bracket; a keyed spindle of a pattern unit for radially locating pattern discs, the inner end of said spindle being located in said pattern unit support; screws which are screwed into the mandrel assembly support and ex-

tend through slots in the base so as to enable the said mandrel assembly support both to be shifted longitudinally on the base and to be swung radially into and out of line with the longitudinal axis of the pattern unit spindle, the screws being appropriately turned to secure the mandrel assembly support in position after it has been turned and moved to correctly locate it relatively to the pattern unit spindle.

16. The invention of claim 15, wherein the mandrel assembly support is pivoted on a shoulder screw the head and shoulder of which are respectively located in a straight longitudinal recess and a slot formed in the base, and is further located by another shoulder screw the head and shoulder of which are respectively located in a partly arcuate recess and slot also formed in the base but being partly straight in the longitudinal direction whereby the mandrel assembly in its support can be swung radially into and out of line on the transfer unit and can also be slid longitudinally with respect to the pattern unit spindle.
